UNITED STATES PATENT OFFICE.

EDWARD J. DOLAN, OF JACKSON HEIGHTS, AND PASCHAL TATORE, OF NEW YORK, N. Y.

THEATER-CURTAIN-RAISING DEVICE.

Application filed July 31, 1926. Serial No. 126,293.

Our invention relates to theatrical appliances and equipment and refers more particularly to apparatus for raising and lowering one or more curtains under electrical control, such as is disclosed in our Letters Patent No. 1,471,454, issued October 23, 1923, of which our present application may be considered as constituting an improvement or modification.

10 An object of our invention is, therefore, to provide improved mechanism whereby a curtain may readily be raised or lowered by means of electrically operated motive power.

Another object of our invention is to provide an improved electrically driven device for manipulating theatrical curtains, whereby reversal of the direction of movement of the curtains may be promptly and effectively controlled with a minimum of attention or effort on the part of the attendant in charge thereof.

20 A further object of our invention is to produce improved mechanism whereby a plurality of curtains or any of them may be separately or simultaneously or alternately raised or lowered by the control of a single person who may be stationed in convenient proximity thereto, the shifting of the curtains in the manner aforesaid being effected by a minimum of effort upon the part of the attendant.

25 A still further object of our improvement is to provide mechanism of the class described which includes automatic controlling means for limiting movement of the curtains in either direction, together with safety means to prevent the mechanism from overrunning and thereby causing breakage of the parts.

The accompanying drawings, illustrative 30 of a preferred embodiment of our invention, are incorporated as part of the present application, of which—

35 Figure 1 is a front elevation of an installation of apparatus employed in connection with portions of the stage structure of a theater showing a lowered curtain suspended upon cords attached to the elevating mechanism of our improvement.

40 Fig. 2 is a partial sectional end elevation projected from Fig. 1, showing two curtains in a lowered position;

45 Fig. 3 is a relatively enlarged sectional side elevation on line 3—3 of Fig. 4;

50 Fig. 4 is a partial top plan view of the structure shown in Fig. 3;

Fig. 5 is a diagrammatic layout of the electric circuits employed; and

Fig. 6 shows an electrical contact detail.

Having reference to the drawings, the numeral 1 is a representation of a curtain or drop scene to be manipulated by our improved means, which is of a usual type employed in theaters, and at its upper and lower edges is reinforced in the ordinary way by curtain sticks 3 to which the fabric of the curtain may be adequately attached in any convenient manner.

50 To the upper stick 3 are assigned a plurality of similar ropes or loops 6, varying in number according to the width of the curtain supported thereby, which loop supports also pass over a pole 5 parallel to and immediately above the top of the curtain, the pole 5 being in turn suspended upon a number of cables which may be increased as required by the width of curtain or the length 55 of the pole supported thereby.

55 The curtain raising cables, in the present form of our improvement, for each full width curtain are three in number, designated respectively as cable 11, 11^a and 11^b, each running over a loose pulley 15 conveniently supported upon a beam 16 which is in turn operably supported upon the uprights or studding of the stage structure of the theater. Each cable is then passed over a second grooved pulley 13 mounted in like manner upon an inclined bracket 14 projecting inwardly and upwardly from the beam 16 to which it is secured, the cables being thence 60 carried downwardly to be in a suitable manner attached to one of the series of multiple drums 20 of the actuating mechanism of our improved apparatus.

65 Thus each drum 20 will be made wide enough to accommodate all of the cables of a single curtain or drop wound upon the periphery thereof, in the present form, three cables being employed to a curtain, as shown in the drawings, the cable 11 being attached 70 at the left hand end of the pole 5 passes over the pulley 15, thence over pulley 13 in the lowermost position on the slanted bracket 14 and is anchored in groove 20 of the drum; the middle cable 11^a in like manner runs 75 over a pulley 15 to the middle pulley 13 of the bracket into groove 20^a of the drum 20; and cable 11^b similarly passes over pulleys 15 and 13 to groove 20^b of the drum.

80 The arrangement last above described

may obviously be repeated for any desired number of scene-curtains, one back of another, each having above it the equivalent of a beam 16, it having been deemed sufficient to show only a second drum and curtain in the drawings to illustrate the unit construction features of our improvement.

We will now proceed to a description of the actuating mechanism and inasmuch as 10 the several probable duplications of the device are substantially identical, a single unit will first be described, giving more attention to details, and then the means will be explained whereby any required number of 15 additional devices of similar construction may be added and operated.

The curtain actuating mechanism is housed within a casing 35, whose dimensions may be increased as required, and which is 20 supported upon legs 36 integral with the side walls 37; end walls 38 (one only shown in the drawings), and a flat bottom portion 39 completing the casing that contains the operating mechanism, next to be described.

25 The drum 20 to which the curtain supporting cables 10 are attached in the manner described is of relatively strong and heavy material and firmly attached in axial alignment therewith to a worm gear 30 loosely 30 mounted upon a non-rotatable shaft 31 and held longitudinally in place by means of the collar 32 pinned to the shaft 31 which is fixedly supported upon the respective end walls 38 of the frame case 35. The drum 35 gear 30 is in mesh with the worm 40 secured by pin 42 to the shaft 41, the shaft 41 being thus disposed transversely to the drum shaft 31 and rotatably mounted at one end upon the side wall 37 and at the other end upon 40 what we shall term the bracket wall 34 projecting upwardly from the floor 39 of the casing. The shaft 41 is also supported intermediate its ends upon brackets 34^a and 34^b similar in form and function to bracket wall 34 already described.

45 Adjacent an end of the shaft 41 and loosely mounted thereon are the first pair of spur gears 50, 51 to the respective inner faces whereof are fixed the oppositely disposed 50 bevel gear rings 55, 56 in axial alignment therewith, which gear rings in turn are in mesh with the bevel pinion 57 keyed or otherwise secured to the shaft 58 which is operably connected with a suitable source 55 of power, such for example as the motor 59.

The gears 50 and 51 are held longitudinally in place on the shaft 41 by means of shoulders 52 formed on the shaft adjacent the inner faces of the gears, the outer faces 60 thereof guided by the respective bracket walls 34 and 34^a; and being driven by a single pinion therebetween, as pointed out, the gears of each pair are caused to rotate in opposite directions, for purposes next to 65 be explained.

Upon the inner faces of the respective gears 55 and 56 are provided outwardly projecting pins 53, 54 which, functioning as clutch teeth, are adapted to be engaged by corresponding pins 63 and 64 of the opposite faces of a clutch member 60 slidably mounted upon the worm shaft 41 by means of a spline 61 suitably provided upon the shaft (shown in broken lines in Fig. 3), the clutch when midway between the gear 75 clutching members 55 and 56 being in a neutral or inoperative position.

For slidably actuating each clutch member 60 we provide a pair of oppositely disposed solenoids 91, 92 suitably secured to 80 the casing floor 39 and having the aligned cores 93, 94 operably supported within the respective coils thereof which, it will presently be seen in connection with the wiring scheme of our device, are adapted to be operated singly or together as may be desired, the winding of each solenoid being such that when energized it will actuate its core in a direction opposite to that of the companion coil. The cores of the respective coils 91, 92 are operably connected to each other and to a forked lever 70 extending through the floor 39 of the casing and pivotally supported thereon by a fulcrum pin 71, as shown in Fig. 3. The upper end of the lever 70 has an arm 74 that branches laterally so as to include the clutch member 60 within the crotch thereof, the rolls 75 suitably mounted upon the inner faces of the forked members being made to enter the annular groove 65 at the opposite sides thereof.

The lever 70 whose primary function is to operate the clutch 60 by the means described, serves an additional function whereby a prolonged arm 76 thereof is made to operate a brake 80 comprising two hinged members 81 operably held within the drums 20, already described, in engaging relationship therewith. These braking members 81, similar in form, are hinged together and supported at the point of union upon an arm 82 preferably pinned or otherwise fixed to the stationary shaft 31, and are normally pressed outwardly against the interior surface of the drum 20 by means of two similar coil springs 84 held in place by the pins 83 which project outwardly from the hub of the bracket arm 82 and into the members 81 of the brake band 80, the springs having each an end resting upon nuts 84^a upon threaded portions of the pins 83 immediately above the hub of the bracket arm 82, the opposite ends thereof bearing outwardly bearing against the members 81 of the brake. Lock nuts 84^b are suitably provided for securely holding the nuts in their adjusted positions to regulate the tension of the springs.

A link or connecting rod 88 is pivotally connected at one end by the shouldered pin 130

to the joined ends of the toggle lever 85, the component members of which are normally carried into straight alignment by action of the springs 84 in applying pressure outwardly to the brake band 80, as shown in Fig. 3; it will thus be seen that if the lever 70 be thrown in either direction in order to actuate the clutch member 60 in the manner already described, the toggle members 81 will also 10 be deflected and shortened, thereby reducing the operable diameter of the brake band 80 and thereby releasing the drum to rotate synchronously with the clutch driven parts.

We have thus described in detail a single 15 unit mechanism for operating a single curtain but our improvement is obviously adaptable to raise and lower any number of curtain drops by the simple expedient of multiplying the drum units, including their actuating and connecting parts, and in the drawings we have shown in partial view a casing adapted to house a plurality of such devices, in connection with which it has been deemed sufficient to illustrate only two unit 20 mechanisms.

Thus a second drum 25 is shown in Fig. 4, with three separate grooves 26, 27 and 28 for receiving the respective cables attached to curtain 2 as shown in Fig. 2, 25 which cables, in the manner already described in connection with curtain 1, pass over respective pulleys 13 of the bracket 14 which is secured to a beam 16, immediately over the curtain, three pulleys 15 mounted directly upon the beam and guiding the cables vertically from the curtain connections.

The drum 25 is in all respects as to form, connecting parts and functions identical with the drum 20 which has been more or less fully described in detail in connection with its associated gear worm 30 and actuating worm 40, and may therefore be considered for purposes of this specification representative of additional drums to any desired 45 number to which other curtains may be attached, preferably in the manner described. Thus, by lengthening the casing 35 and with it the stationary shaft 31 upon which the worm gears 30 and drums 20 are loosely 50 mounted, the duplication of the above described units as already seen may be effected by providing additional shafts 41 in parallel arrangement, each immediately beneath a corresponding drum gear 30 and provided with an actuating worm 40 in mesh therewith and actuated in the manner described.

The added shafts 41 will be rotatably supported upon bearings in the side walls 37 and bracket walls 34, 34^a and 34^b in the manner hereinabove described and will be provided with the right and left hand spur gears 50^a, 51^a with pins or teeth 53 and 54 respectively provided therein and adapted to engage corresponding teeth of clutch similar to the member 60 already described, the

gears 50^a, 51^a being in mesh with the like gears 50, 51. The gears 50, 51, it has been seen, have attached thereto the bevel gear rims 55, 56 in mesh with an actuating pinion connected with the operating source of power, the gears 50^a and 51^a and succeeding pairs of similar spur gears as required, all being in mesh, as shown in Fig. 4, and driven by the original pair 50, 51, do not require other means for their actuation; and it has been seen that the gears 50 and 51 rotate oppositely, being driven by the same intermediate pinion, and it will likewise be understood that the respective gears of the adjacent pair will also rotate in opposite directions as will all succeeding pairs similarly connected.

Thus in order to have the drums 20, 25 rigged uniformly in the manner described, to operate to raise or lower their respective curtains 1 and 2, the clutches 60, 60^a 85 of adjacent shafts 41 will be required to be shifted oppositely to produce identical action, that is to say, will move one to the right and the other to the left in order to raise the two curtains 1 and 2 at the same time, or to lower them simultaneously. It has been deemed important to point out the arrangements and operations of the chain gears as above, to better understand the diagrammatic wiring scheme illustrated in Fig. 5 and presently to be described. It will, however, be readily understood that the clutch members 60, 61 would all move in unison in a given direction to raise (or to lower) all the curtains simultaneously, providing the cables running to the curtain should be differently wound upon succeeding drums, one drum having its cables attached at one side, the drum next in order having its cable come down to the periphery thereof upon the side opposite that of the adjacent drums, other connections remaining the same throughout.

Before presenting the schematic diagram of the electric circuits employed in connection with our apparatus, we shall describe the automatically operable mechanical means for shutting off the power that actuates the mechanism if the operator should fail to do so when any curtain shall have reached the limit of its upward travel. Thus, in order to preclude the mechanism from over-running and carrying a curtain beyond its limits, we have provided a circuit breaking mechanism whereby the rising curtain, by its own action, cuts off the current that runs the motor, when the curtain starts to travel above a predetermined point. In the preferred form illustrated in the drawings, this important end is accomplished by means of a rod 95 of non-conductive material, having therein bands 95^a of metal or other electro-conductive material, which bands are held in the looped portions of not less than two similar U- 130

shaped hanging brackets (one only shown) which are suspended directly over the series of curtains 1, 2, disposed so as to be contacted by the poles 5 of the curtains 5 transversely thereof about midway of their length.

At the bottom of each loop-hanger is provided terminals 97 suitably insulated by any convenient dielectric material as shown in 10 Fig. 6, upon which terminal members the respective electro-conductive bands 95^a at the ends of the rod 95 rest, electrically closing the circuit between them.

Thus the conductive bands 95^a themselves 15 act as terminals to which are connected the wires of the motor circuit, from which it will follow that when one of the poles 5 engages the under side of the rod 95 transversely thereof, the latter member will be 20 raised, thereby carrying the conductive bands 95^a out of contact with the terminals 97 in the manner described, thereby breaking the motor circuit and shutting off the power at its source to prevent carrying the 25 curtain beyond the upward limit of its travel.

An additional precaution has been provided to forestall an overrun of the actuating mechanism in either direction by means of providing a thread 45 upon each of the 30 shafts 41 upon which screw portion is mounted a traveling nut block 46 which has a depending extension 47 that enters a slotted opening or recess 39^a in the bottom 39 of the casing 35, whose side walls guide 35 the block as it is carried forward and back by means of the screw when the shaft is caused to rotate in either direction.

At the respective ends of the passageway 39^a is suitably placed any convenient form 40 of electrical switches or circuit breaking devices 48, 49 in order to shut off the current that energizes the solenoids of the unit to which it relates, and in order to effect this break of circuit at different points, these 45 switches are adjustably mounted and held in place across the slots 39^a by bolts 39^b (see Fig. 3).

Thus is provided additional means for safeguarding the mechanism from overrunning in either direction, that is, while the block 46 is traveling toward switch 48 at the left hand end of the slot 39^a or towards 49 at the right hand end thereof.

We will now explain the wiring diagram 55 as contained in Fig. 5, in which the armature 100 of the motor is indicated with two brushes 101, 102 respectively, which are connected to the source of power by means of the conductors 110 and 120, as shown. The 60 usual rheostat 150 in series in conductor 110 is provided for regulating the speed of the motor and both conductors may be broken at either terminal 97 by means of the terminal band 95^a being lifted by any one of 65 the curtains 1, 2 in the manner hereinabove

described, the usual solenoid operated brake being supplied for the motor and indicated at 99 in this circuit.

A third conductor 130 connects to the electrical source and with the conductor 120 70 forms the circuit to supply the current with which all the solenoids are operated, the conductor 130 as shown comprising in series therein a plurality of duplex switches, one for each pair of solenoids 91, 92 that operate a curtain, each switch comprising the two switch blades 113, 143. The blade 113 connects with a terminal of the conductor 112 which runs to one side of the solenoid 91, then through the coil of the solenoid to 80 the other side thereof, thence through conductor 111 to the main conductor 110. The other blade 143 of the switch similarly completes a circuit through conductor 142 to solenoid 92, thence and through conductor 85 141 to trunk 120.

As has been seen, a switch member 48 is provided within the circuit that includes the solenoid 91 and in similar manner a switch 49 is operated by the traveling nut or 90 block 46 upon the shaft 41 to break the circuit that supplies the current to solenoid 92 at the respective limits of the movement, which are shown in the diagrams in conductors 112 and 142 respectively. 95

The trunk line 130 may also have in series therewith, if desired, a pair of switch terminals 97 which are engaged by contact members 95^a on the switch rod 95 for breaking the current that electrifies the solenoids 91, 92 in the manner described, so as to provide that all the solenoid circuits may be discontinued by action of any one of the curtains being carried above its intended run, and, as has already been explained, each 100 solenoid singly by action of its own automatically operated switch will break the motor circuit when it has raised or lowered its curtain to the extent required. 105

The diagram, Fig. 5, is plotted for a layout to include six pairs of solenoids to operate six curtains or drops, it being understood that the number of solenoid pairs may be increased as desired by following the plan of the diagram as hereinabove explained. 110

We claim:

1. In a device having a rotatable drum for raising and lowering curtains, a worm gear loosely mounted upon a non-rotatable shaft and operably supporting said drum; a worm keyed to a rotatable shaft and in mesh with said gear; a pair of oppositely disposed spur gears loosely mounted upon said rotatable shaft; a clutch member splined on said shaft intermediate said spur gears; engaging teeth upon both faces of said clutch member and upon the adjacent faces of said gears; an electrically driven motor for actuating said spur gears; solenoids for alternately actuating said splined member into 120 125 130

tooth engagement with said spur gears; automatic means operated by said curtain for shutting off the current from said motor; and adjustable means operated by the solenoids for shutting off the current to either of said solenoids.

2. In a device having a rotatable drum for raising and lowering theatrical curtains, a plurality of cables connecting each of said curtains to a drum; a worm gear loosely mounted upon a non-rotatable shaft and operably supporting said drum; a worm keyed to a rotatable shaft transversely disposed to said non-rotatable shaft in mesh with said drum supporting gear; a pair of oppositely driven spur gears loosely mounted upon said rotatable shaft, a clutch member splined to said shaft therebetween; means comprising a pair of solenoids for 20 sliding said intermediate clutch member to operably engage either of said spur gears; and adjustable means on said last mentioned shaft for automatically breaking the circuit that energizes the solenoid that is active, said 25 means comprising a thread upon said shaft, a traveling member thereon, and circuit breaking switches adjustably attachable at any predetermined point of the travel of said member.
3. In a unit device having rotatable drums for raising and lowering theater curtains, a non-rotatable shaft having a plurality of worm gears loosely mounted thereon and operably supporting said drums; a series of

parallel shafts rotatably disposed transversely to said first mentioned shaft, each rotatable shaft having a worm pinned thereon in mesh with a worm gear, a pair of loosely mounted spur gears with laterally projecting clutching teeth and a splined 35 clutch member intermediate said gear members having clutch teeth upon its respective faces corresponding to said first mentioned teeth; a series of oppositely disposed solenoids corresponding in number and arrangement to said rotatable shafts and means comprising a system of electric circuits for energizing any one or more of said solenoids.

4. In a device having a rotatable drum for raising and lowering theater curtains, means for operating said drum comprising oppositely rotatable gear members loosely mounted upon a rotatable shaft and a 50 slideable member therebetween splined to said shaft; a spring actuated brake supported 55 within said drum and normally holding the same against rotation; solenoids for reciprocating said slideable member; means comprising a lever pivotally supported adjacent said solenoids and adapted to slide said 60 member into engagement with either of said gear clutch members and simultaneously releasing said brake.

In testimony whereof we have hereunto set our hands.

EDWARD J. DOLAN.
PASCHAL TATORE.
